UNITED STATES PATENT OFFICE.

ARTHUR O. HUBBARD, OF MINNEAPOLIS, MINNESOTA.

SILO.

1,030,405.

Specification of Letters Patent. Patented June 25, 1912.

Application filed September 5, 1911. Serial No. 647,653.

To all whom it may concern:

Be it known that I, ARTHUR O. HUBBARD, of Minneapolis, Hennepin county, Minnesota, have invented certain new and useful

5 Improvements in Silos, of which the following is a specification.

My invention relates to that type of silos in which the walls are composed of upright panels and bars arranged vertically at the 10 joints between the abutting panels.

The object of the invention is to provide means for securing together the abutting ends of the sections composing the bars to the end that the erection of the silo may 15 be facilitated.

A further object is to provide a coupling device which will be simple and economical in construction and will hold the sections rigidly in alinement with one another.

20 The invention consists generally in various constructions and combinations, all as hereinafter described and particularly pointed out in the claims.

In the accompanying drawings forming 25 part of this specification, Figure 1 is an outside view of the lower portion of a silo with my invention applied thereto, Fig. 2 is a sectional view showing the meeting edges of the abutting panels and the bar 30 provided at the joint between the panels. Fig. 3 is a front view of the coupling means between the bar sections. Fig. 4 is a side view illustrating the abutting ends of vertically arranged bars with the coupling 35 bridging the joints between said ends, the coupling being shown partially in section to illustrate the locking keys.

In the drawing, 2 represents the panels of which the silo is composed.

40 3 is a section of the upright rails or bars provided at the joints between the vertical edges of the abutting panels. This section has preferably an inwardly projecting flange 4, laterally extending flanges 5 and an outwardly projecting flange 6. When the sections are placed end to end in alinement with one another they form a continuous bar extending from the bottom to the top of the silo, the sections being added on as 45 the silo is built. To unite or couple together the abutting ends of the sections, I provide a rail 7 consisting preferably of a

50 U-shaped in cross section, adapted to fit onto the flange 6 of the abutting rail. The sections and having outwardly turned edges 8 which fit

snugly against the flanges 5. Slots 9 are provided in the looped portion 7 and in the flange 6 to receive locking keys 10 which are driven therein and have their ends outwardly turned to prevent them from slipping out of the slots. The abutting sections are thus securely held together and as the edges 8 have broad bearing surfaces on the flanges 5 the coupling will be very rigid and will hold the sections as securely as though the bars were formed in one piece. I also prefer to provide a recess 11 in the loop 7 to receive a hoop 12 and form a seat therefor. The bars are made of a suitable weight of 50 metal and the coupling rails are preferably stamped or pressed out of metal of suitable gage and formed to fit-snugly on the flanges 6 and against the outer faces of the flanges 5.

60 The details of the construction may be 65 varied without departing from my invention.

I claim as my invention:

1. The combination, with the upright silo panels having abutting vertical edges, of 70 vertically arranged metal bars composed of sections placed end to end, one above another, said bars comprising outwardly projecting flanges and side flanges adapted to bear on the panels of the silo, rail plates 75 seated on said outwardly projecting flanges and having their edges bearing on said side flanges and bridging the joints between the abutting sections of said bars, and tongues 80 passing through said plates and outwardly 90 projecting flanges and locking said sections in vertical alinement.

2. A silo composed of upright panels having vertical abutting edges, metal bars provided at the joints between abutting panels, 95 said bars being composed of sections placed end to end and having outwardly projecting flanges and side flanges adapted to bear on the walls of said panels, coupling rails bent to fit over said outwardly projecting flanges and having edges that are seated upon said side flanges, said rails bridging the joints between the sections of said bars, hoops 100 inclosing the silo and seated on said rails, and means for securing said rails to the outwardly projecting flanges of said bars.

3. In a silo, upright metal bars provided at the joints between the vertical sections of the silo, said bars being composed of sections placed end to end, each section being 110 provided with laterally projecting flanges adapted to bear on the outer surfaces of the

silo sections, said sections also having outwardly projecting flanges, and rails, U-shaped substantially in cross section, fitting said outwardly projecting flanges and 5 bridging the joints between said sections, and having upwardly turned edges seated on said laterally extending flanges, and means securing said rails to said sections.

4. In a silo, upright bars composed of sections placed end to end, each section having 10 laterally extending flanges adapted to bear

on the walls of the silo and also having outwardly projecting flanges, rails bridging the joints between the abutting sections, and locking keys passing through slots in said rails and said outwardly projecting flanges.

In witness whereof, I have hereunto set my hand this 29th day of Aug., 1911.

ARTHUR O. HUBBARD.
